UNITED STATES PATENT OFFICE

ALFRED VEILLETTÉ, OF ATTLEBORO, MASSACHUSETTS

DESIGN FOR A BRIDGE MEMBER FOR AN OPHTHALMIC MOUNTING

Application filed April 2, 1932. Serial No. 43,373. Term of patent 3½ years.

To all whom it may concern:

Be it known that ALFRED VEILLETTÉ, a citizen of the United States, residing at Attleboro, in the county of Bristol and State of Massachusetts, has invented a new, original, and ornamental Design for a Bridge Member for an Ophthalmic Mounting, of which the following is a specification, reference being had to the accompanying drawing, forming a part thereof.

Fig. 1 is a front elevational view of a bridge

member for an ophthalmic mounting showing my new design.

Fig. 2 is a transverse vertical view through the center section of the bridge member shown in Fig. 1 and

Fig. 3 is a plan view of the same.

I claim:

The ornamental design for a bridge member for an ophthalmic mounting as shown.

In testimony whereof I affix my signature.

ALFRED VEILLETTÉ.
